6 Claims. (Cl. 179—171)

1

The present invention relates to electric amplifying devices employing semi-conducting materials, which have been called for convenience "crystal triodes."

It is already known that certain crystalline semi-conducting materials are suitable for use as point-contact rectifiers (generally known as crystal detectors) and that such material may be made to act as an amplifier by mounting a body of the material on, or in, a suitable metal base or holder which makes electrical contact with the body over an extended area, and by providing it with two fine wire electrodes or cat whisker arranged very close together in contact with the surface of the body. By suitably polarising the electrodes with respect to the base the device can be made to operate as an amplifier similarly to a thermionic valve, and for this reason the device has been called a "crystal triode" by analogy. However, the word "triode" is not intended to be restricted to a device having just three electrodes, for as in the case of thermionic valves, there may be additional electrodes employed for control purposes.

In such crystal triodes known hitherto, two cat whisker electrodes are provided, and one of them, called the emitter electrode, is polarised with respect to the base electrode in the good conducting or low resistance direction, while the other, called the collector electrode, is polarised with respect to the base in the poor conducting or high resistance direction. The best semi-conducting material at present known for this purpose is germanium, and a suitable material for the cat whisker is Phosphor bronze.

The amplifying action in a crystal triode is generally supposed to result from interaction between the collector and emitter currents, and the control of the collector current by the emitter current can therefore be modified if the amount of inter-action can be modified.

The amount of interaction between the collector and emitter currents may be increased by reducing the cross-section of the semi-conductor at the point where the electrodes make contact, and by constraining the collector and emitter currents so that they both flow mainly through the reduced portion of the semi-conductor. This is accomplished according to the present invention by providing an electric amplifying device comprising a body of semi-conducting material consisting of two main portions connected by an intermediate portion of smaller cross-sectional area than either of the main portions, a collector electrode and an emitter electrode, each making

2

rectifier contact with the surface of the intermediate portion of the material, two base electrodes in contact respectively with the two main portions, and means for separately biasing the collector and emitter electrodes each with respect to a corresponding one of the base electrodes in such manner that both the emitter and the collector currents are constrained to flow in the same part of the said intermediate portion.

One way of carrying out the invention is to mount the semi-conductor on a base electrode or holder in the usual way and then to make a saw-cut through the holder and semi-conductor so that the latter is nearly, but not quite, divided into two separate portions. The two cat whiskers will be placed on the semi-conductor surface just above the saw-cut, and each will then be biased separately to one of the base portions in the manner described in the specification of British Patent No. 682,206 dated February 25, 1953 of K. A. Matthews for "Crystal Triode-divided Base Electrode" with, however, the further requirement that a cross-biasing should be used, that is each cat whisker should be biased with respect to the base portion on the other side of the saw-cut, whereby the collector and emitter currents are constrained to flow largely in the same direction in the reduced cross-section of the semi-conductor.

The conditions of the invention may be fulfilled in various other ways. For example, if the saw-cut be made sufficiently wide, the two cat whiskers could be placed in contact with the semi-conductor at the bottom of the slot instead of on the outside face of the semi-conductor.

If necessary the two base electrode portions may be effectively connected together, as regards the frequencies contained in the signal to be amplified, by connecting them with a blocking capacitor.

The invention is illustrated in the drawing in which Fig. 1 shows a sectional view of an amplifying device according to the invention, together with the associated circuit, and Fig. 2 shows a modified arrangement according to the invention.

In Fig. 1, the amplifying device consists of a body 1 of germanium or other suitable semi-conductor, having two base electrodes 2, 3 each of which makes contact with the semi-conductor over an extended area. The semi-conductor 1 has cut therein a narrow slot or crevasse 4 which almost, but not quite, divides it into two separate portions, which are connected by a very thin portion 5. The device might, for example, have been made by fixing a disc or plate of semi-conductor

in a metal holder, and cutting a slot through the holder and semi-conductor to form the crevasse 4. The emitter and collector electrodes 6 and 7 consist of cat whisker, shown as arrow heads, making point-contact with the surface of the semi-conducting body 1 at the narrow portion 5 just above the top of the crevasse 4. The cat whisker should preferably be made from Phosphor bronze wire.

The emitter electrode 6 is biassed positively with respect to the base electrode 3 on the opposite side of the crevasse 4 by a source 8, having a potential not more than about 1 volt. The source 8 is connected to the emitter electrode 6 through the secondary winding of an input transformer 9, the primary winding of which is connected to a pair of input terminals 10, 11 to which the signals to be amplified are supplied.

The collector electrode 7 is biassed negatively with respect to the other base electrode 2 by a source 12 having a potential which may be anything from 5 to 50 volts. The source 12 is connected to the collector electrode 7 through the primary winding of an output transformer 13, the secondary winding of which is connected to a pair of output terminals 14, 15 which may be connected to a load circuit (not shown) to which the amplified signals are to be delivered.

The two base electrodes 2 and 3 are connected by a large blocking capacitor 16 to bring them substantially to the same potential at signal frequencies.

For the above description it has been assumed that the semi-conducting material is of the N-type, such as germanium, for example. If P-type material is used, each of the bias sources 8, 12 should be reversed. A brief explanation of the difference between N- and P-type semiconducting material will be found in U. S. Patent No. 2,653,374 dated September 29, 1953, of K. A. Matthews-C. de B. White for "Electric Semiconductor," and assigned to the same assignee as the present application.

It will be seen that with the arrangement shown the emitter and collector currents are both constrained to flow in the portion 5 of reduced cross-sectional area, and as each electrode is biassed with respect to the base electrode on the opposite side of the crevasse 4, the two currents are forced to mix, and the degree of interaction is thereby increased.

Fig. 2 illustrates the second type of arrangement alluded to in the earlier part of this specification. Corresponding elements are given the same designations as in Fig. 1.

The crevasse or slot 4 is made wide enough to enable the electrodes 6 and 7 to make contact with the semiconductor inside the crevasse 4 instead of outside; otherwise the arrangement is essentially the same as shown in Fig. 1.

While the principles of the invention have been described above in connection with specific embodiments, and particular modifications thereof, it is to be clearly understood that this description is made only by way of example and not as a limitation on the scope of the invention.

What is claimed is:

1. An electric amplifying device comprising a body of semi-conducting material having two main portions and an intermediate portion interconnecting said two main portions, said intermediate portion being of a lesser thickness than either of said main portions to define a channel therebetween a collector electrode and an emitter electrode, rectifier contact means for

each of said electrodes each contacting the surface of said intermediate portion of the material, two base electrodes in contact respectively with the two main portions, and means separately biassing the collector and emitter electrodes each with respect to a corresponding one of the base electrodes in such manner that both the emitter and the collector currents to the base electrodes are constrained to flow in the same part of the said intermediate portion, said contact means for the electrodes being spaced apart and so located that each engages the intermediate portion between the other contact means and that main portion to the base electrode of which said other contact means is connected through its bias means.

2. An electric amplifying device comprising a body of semi-conducting material having a slot therein dividing it nearly but not quite into two separate portions, two base electrodes in contact respectively with the said two portions, a collector electrode and an emitter electrode, rectifier contact means for each of said electrodes, each of said contact means making rectifier contact with the surface of semi-conducting material on the narrow portion formed by said slot, and means for separately biassing the collector and emitter electrodes each with respect to one of the base electrodes, in such manner that the collector and emitter currents to the base electrodes are constrained to flow in the same part of the said narrow portion, said contact means for the electrodes being spaced apart and so located that each engages the intermediate portion between the other contact means and that main portion to the base electrode of which said other contact means is connected through its bias means.

3. An amplifying device according to claim 2 in which the collector and emitter electrodes and contact means comprise cat whisker making point-contact with the surface of the said narrow portion on the face remote from the end of the slot.

4. An amplifying device according to claim 2 in which the collector and emitter electrodes and contact means comprise cat whisker arranged in the slot and making point-contact with the said narrow portion at the blind end of the slot.

5. An electric amplifying device comprising a body of semi-conducting material provided with a transverse slot to divide said material into a pair of main portions interconnected by a relatively thin bridge-like portion, a base electrode maintained in contact with each of said two main portions, a pair of cat whisker type electrodes maintained in engagement with the surface of said bridge-like portion in closely spaced relation one to the other, and means for separately

biassing said collector and said emitter electrode each with respect to one of the base electrodes, whereby collector and emitter currents to the base electrodes are constrained to flow in substantially the same direction through the same part of said bridge-like portion, said cat whisker electrodes being spaced apart and so located that each engages the intermediate portion between the other cat whisker electrode and that main portion to the base electrode of which said other cat whisker electrode is connected through its bias means.

6. An electrical amplifying device comprising a body of semi-conducting material provided with a transverse slot to divide said material into a pair of main portions interconnected by a rela-

tively thin bridge-like portion, a base electrode maintained in contact with each of said two main portions, a pair of cat whisker type electrodes maintained in engagement with the surface of said bridge-like portion in closely spaced relation one to the other, the engagement point of each cat whisker with the surface of the bridge-like portion being closer to one of the base electrodes than the engagement point of the other cat whisker electrode, means for biasing the emitter electrode with respect to the base electrode furthest removed therefrom to produce a current flow across the bridge-like portion in a

given direction, and means for biasing the collector electrode with respect to the base electrode furthest removed therefrom to produce a current flow across the bridge-like portion in the same direction as said given direction.
